OVER ICE CHILLER

Eugene L. Bud Brown, San Jose, Calif.

Application May 20, 1952, Serial No. 288,973

4 Claims. (Cl. 62—146)

This invention relates to a bar accessory and more particularly to an over ice chiller for liqueur and like aromatized spirits.

Liqueur as a class of beverage is a highly concentrated form of spirituous liquor which is flavored with aromatic substances. Cordials and brandies, for example, come within the class of beverages which are served in small portions not for the volume of liquid dispensed but for the distinct, agreeable and pungent flavor and aroma they afford.

There are many different flavors and brands of liqueur available and since the call for such delicacies is dependent upon the taste of each individual it is not the practice to keep the bottled liqueur on ice. Moreover, it is not a liquid that is best suited to consumption when extremely ice cold because the aromatic flavors are most pungent at higher than ice cold temperature. Furthermore, since liqueur is a beverage which is mainly enjoyed through the sense of taste and smell it is sipped and mouthed rather than swallowed immediately. Consequently some connoisseurs of fine liqueur like it at room temperature whereas others prefer to have it chilled slightly, particularly when room temperature is such that the liqueur in the bottle is warmer than desired.

From the foregoing it will be apparent that a problem arises in satisfying the fastidious and discriminating persons who order and partake of liqueur. In addition thereto, any chilling of such aromatized beverages by pouring them into a glass containing ice gives rise to the further problem of not only over-cooling but worse still a diluting of the liqueur, thereby causing loss of their pungency.

The present invention contemplates overcoming the foregoing problems in a simple yet effective manner by the provision of an over ice chiller which assures a minimum of dilution of liqueur and a proper yet not too great a chilling thereof while it is being poured.

Another object is to provide a device for supporting ice in a manner to cause liqueur poured thereover to wash over the ice as the liqueur gravitates into a liqueur glass.

Yet another object is to provide a trough-like support for supporting a plurality of cubes of ice in spaced relation to the walls of the trough whereby liquid poured slowly over the ice will adhere to the ice during gravitational travel toward and along the floor of the trough.

A further object is to provide an ice cube supporting trough with an open spigot end for training fluid which gravitates from the ice cubes into a small mouthed container such as a liqueur glass.

These and other objects of the present invention will become apparent from a reading of the following description and claims in the light of the drawings, in which:

Fig. 1 is a perspective view portraying my over ice chiller in use.

Fig. 2 is an enlarged perspective view of the over ice chiller shown in Fig. 1.

Fig. 3 is an end view of Fig. 2 as seen from line 3—3 thereof.

2

Fig. 4 is a longitudinal section of Fig. 2 taken along line 4—4 thereof; and

Fig. 5 is a cross section of Fig. 4 taken along line 5—5 thereof.

5 Referring to Figs. 1, 2 and 4, the over ice chiller of the present invention, designated generally by reference numeral 10, comprises an elongated tray which is preferably long enough to support one or more cubes of ice of the standard size and shape.

10 Since ice is most frequently provided in the form of a cube, the over ice chiller 10 in the present disclosure has a trough-like body 11 which has its sides 12 and 13 disposed at right angles to each other and joined at their contiguous edges to provide a fluid retaining floor or valley 14. In this connection, the body 11 is made or formed from a single piece of material and preferably is moulded in plastic material, although metals, glass and/or porcelain are equally adapted for the purpose.

15 At one end of the main body 11 the side walls 12 and 13 are closed by an end wall 15. The opposite ends of the side walls 12 and 13 terminate in extensions 12'—13' respectively, which form a tapering spout or spigot 16 which curves downwardly and away from the floor 14 of the valley formed by the two side walls.

20 At the point where the side walls 12 and 13 merge with and become the downturned spout 16 they are joined by a cross bar 17 which serves to rigidly secure the side walls in proper rectangular disposition. This cross bar 17 has its upper edge 18 at the same plane with the upper edges of the side walls 12 and 13. The lower edge 19 of the cross bar 17 is disposed substantially at the upper edges of the side walls 12'—13' of the spout 16. However, it should here be noted that for all purposes and intent the cross bar 17 affords an opening 20 at the end of the chiller where the trough-like body merges with the spout 16 and serves mainly to maintain the first ice cube within the trough formed by the body 11 and to prevent the ice cubes from gliding out to and over the spout 16.

25 The inner surfaces of the two side walls 12 and 13 are each provided with projections 21 (see Figs. 2, 4 and 5) which will engage the cubes of ice and suitably support them in spaced relation relative to the inner surfaces of the side walls of the trough-like body 11, see particularly, Fig. 5. For purposes of the present disclosure I have shown the projections 21 as dome-like knobs which are spaced along the side walls 12—13 such that each ice cube will engage one or more of them (Fig. 4) and be thereby supported sufficiently clear of the inner surfaces of the side walls as well as the valley 14 between them as to allow fluid flowing over the ice cubes to pass right on through such clearance spaces and out through the opening 20 onto the spout 16 for direction thereby into a glass.

30 The main body 11 of the trough may be provided with a lateral extension 25 affording a handle by which the chiller 10 can be manipulated. This extension 25 is provided with a recess 26 forming a seat for the pad portions of the thumb and first finger of a person's hand. This recess 26 may be cut clear through to provide an aperture by which the chiller can be hung on a nail or hook when not in use.

35 In use, the over ice chiller of the present invention is held by its extension 25 in the manner as shown in Fig. 1. A plurality of ice cubes are placed in the trough-like body 11, as best seen in Fig. 4. The person holding the chiller can now grasp a bottle of liqueur with his free hand while manipulating the chiller with his other hand, so that the spout 16 is directly over the mouth of a liqueur glass. Although the body 11 is tilted with its spout portion 16 lowest, it will be seen that the ice cubes are maintained within the trough-like portion of the main body by the cross bar 17.

40 Now as the liquid is poured gently onto the ice cubes

for chilling, the liquid glides over the ice, adhering thereto as it flows into the spaces afforded between the ice cubes and side walls 12 and 13 by the projections 21. As a matter of fact, as the liquid gravitates along the valley 14 toward the opening 20 and spout 16 it is touching the lowermost tips of the ice cubes and thereby chilled.

From the foregoing it will be appreciated that there is a minimum amount of melting of the ice cubes as the chilling of the liquid takes place with my device. Consequently, the liquid flowing from the spout 16 and into the liqueur glass is adequately chilled with a minimum danger of diluting the liquid. The entire operation takes place so fast that the ice cubes usually still have some of the liqueur on them after the pouring into one or several liqueur glass has ceased.

While I have described my new over ice chiller in specific detail, it will be apparent that its structure can be modified, altered and/or varied somewhat without departing from the spirit of my invention. I therefore desire to avail myself of all modifications, alterations and/or variations as fairly come within the purview of the appended claims.

What I claim as new and desire to protect by Letters Patent is:

1. A device for chilling liqueur during pouring of the same from a bottle into a small mouthed glass comprising an elongated open trough-like body having a pair of side walls disposed at a substantially right angle to each other and joined at their contiguous edges to provide a valley bottom, a wall at one end of said side walls for closing that end of said trough-like body, a cross bar joining the upper portions of the opposite ends of said side walls for maintaining cubes of ice in said trough-like body and cooperating with the latter to form an opening in said opposite end of said trough-like body, and a spout formed integrally with said side walls and extending beyond said opposite end thereof for directing liqueur poured onto the ice cubes in said trough-like body for continuous flow into a small mouthed glass.

2. A device for chilling liqueur during pouring of the same from a bottle into a small mouthed glass comprising an elongated open trough-like body having a pair of side walls disposed at a substantially right angle to each other and joined at their contiguous edges to provide a valley bottom, a wall at one end of said side walls for closing that end of said trough-like body, a cross bar joining the upper portions of the opposite ends of said side walls for maintaining cubes of ice in said trough-like body and cooperating with the latter to form an opening in said opposite end of said trough-like body, a spout formed integrally with said side walls and extending beyond said opposite end thereof for directing liqueur poured onto the ice cubes in said trough-like body for continuous flow into a small mouthed glass, and a plurality of inwardly extending projections on said side walls for sup-

porting cubes of ice in spaced relation relative to said side walls and the valley bottom formed thereby.

3. A device for chilling liqueur during pouring of the same from a bottle into a small mouthed glass comprising an elongated open trough-like body having a pair of side walls disposed at a substantially right angle to each other and joined at their contiguous edges to provide a valley bottom, a wall at one end of said side walls for closing that end of said trough-like body, a cross bar joining the upper portions of the opposite ends of said side walls for maintaining cubes of ice in said trough-like body and cooperating with the latter to form an opening in said opposite end of said trough-like body, said side walls extending outwardly and downwardly from a point beyond said cross bar in the form of a spout extending beyond said opposite end of said trough-like body for directing liqueur poured onto the ice cubes in continuous flow into a small mouthed glass, and a plurality of inwardly projecting knobs on each of said side walls for supporting cubes of ice in spaced relation thereto and relative to the valley bottom provided thereby to afford unobstructed flow of liqueur along said valley bottom and into said spout.

4. A device for chilling liqueur during pouring of the same from a bottle into a small mouthed glass comprising an elongated open trough-like body having a pair of side walls disposed at a substantially right angle to each other and joined at their contiguous edges to provide a valley bottom, a wall at one end of said side walls for closing that end of said trough-like body, a cross bar joining the upper portions of the opposite ends of said side walls for maintaining cubes of ice in said trough-like body and cooperating with the latter to form an opening in said opposite end of said trough-like body, said side walls extending outwardly and downwardly from a point beyond said cross bar in the form of a spout extending beyond said opposite end of said trough-like body for directing liqueur poured onto the ice cubes in continuous flow into a small mouthed glass, a plurality of inwardly projecting knobs on each of said side walls for supporting cubes of ice in spaced relation thereto and relative to the valley bottom provided thereby to afford unobstructed flow of liqueur along said valley bottom and into said spout, and a lateral extension on one of said side walls adjacent the walled end of said trough-like body for manipulating the latter with one hand while liqueur is poured into the same from a bottle held in the other hand.
